UNITED STATES PATENT OFFICE.

CHARLES AUGUSTUS COPELAND, OF ROCKLANE, INDIANA.

STEERING APPARATUS FOR TRACTION-ENGINES.

SPECIFICATION forming part of Letters Patent No. 394,460, dated December 11, 1888.

Application filed September 19, 1888. Serial No. 285,807. (No model.)

To all whom it may concern:

Be it known that I, CHARLES AUGUSTUS COPELAND, a citizen of the United States, residing at Rocklane, in the county of Johnson 5 and State of Indiana, have invented a new and useful Improvement in Steering Apparatus for Traction-Engines, of which the following is a specification.

My invention relates to an improvement in steering apparatus for traction-engines; and it consists in the peculiar construction and combination of devices, that will be more fully set forth hereinafter, and particularly pointed out in the claim.

15 In the accompanying drawings, Figure 1 is a side elevation of a traction-engine provided with steering apparatus embodying my improvements: Fig. 2 is a top plan view of the same. Fig. 3 is an inverted plan view. Fig. 20 4 is a detail view.

A represents a traction-engine of the usual construction, which is provided with the rear axle, B, having the driving-wheels C and gears D, and the pivoted front axle, E, having the 25 wheels F.

The engine G is arranged on one side of the boiler, in the usual manner, and imparts rotary motion to the usual crank-shaft, H, which is in turn connected by suitable means (not 30 shown) to a counter-shaft, I, which has pinions K, that engage the wheels D.

L represents a longitudinal shaft, which is journaled in suitable bearings, M, on one side of the boiler, and is connected with the shaft 35 H by a pair of miter gear-wheels, N O.

P R represent a pair of miter friction-wheels, which are secured to the shaft L near the rear end thereof, and at suitable distances apart, and the said friction-wheels are arranged on 40 the said shaft with their miter faces opposed to each other.

The bearing M, in which the rear end of shaft L is journaled, has a horizontal portion, S, which is provided with a longitudinal slot, T.

45 U represents a vertical shaft, which has its lower end stepped in a bearing, V, that projects from one side of the furnace. The upper portion of the said shaft U extends through the slot T, and is adapted to move back and 50 forth in the said slot.

W represents a lever, which is arranged on one side of and is provided with the usual

spring-actuated bolt or detent that is adapted to engage a sector-plate, X, whereby the lever may be maintained in any desired position. 55 A link-rod, Y, connects the lever W to the upper end of the shaft U, and thereby the said shaft U may have its upper end moved forward or rearward by operating the lever W, as will be very readily understood. 60

To the lower end of the shaft U is attached a worm, Z, and to the said shaft, at a slight distance from its upper end, is rigidly secured a miter friction-wheel, A', which is adapted to engage with either wheel P or the wheel R, 65 according to the inclination of shaft U.

B' represents a shaft or winch, which is journaled in bearings C', that project from the front side of the furnace, said shaft or winch being thereby arranged transversely on the 70 front side of the furnace and under the boiler, as shown.

C' represents a worm-wheel, which is rigidly secured to the said shaft or winch, and is engaged by the worm Z. 75

D' E' represent a pair of chains, which are attached to the pivoted front axle near opposite ends thereof, and have their inner ends attached to the winch or drum B' and coiled thereon in opposite directions. 80

The object of my invention is to provide a steering apparatus which is operated by the engine, and which may be readily controlled by the driver or engineer, whereby the engine may be directed very readily and without any 85 physical exertion on the part of the person operating the same.

This steering-gear has been hereinbefore described, and the operation thereof is as follows: While the engine is proceeding along a 90 road the crank-shaft H is in constant rotation and the beveled gears N O impart rotary motion to the shaft L. While the engine is traveling in a straight line the lever W will be turned to a vertical position, so as to arrange the shaft U in the vertical position, and thus keep the friction-wheel A' out of engagement with the wheels P R; hence the shaft U will not be rotated, and consequently the shaft B', which is geared thereto, will remain stationary and will not affect the front axle, E. When it is desired to turn the engine to the right, the lever W will be moved so as to draw the upper end of the shaft U rearward, 95 100

and thereby cause the friction-wheel A' to engage the wheel P, and thus impart rotary motion from the shaft L to the shaft U, cause the worm Z and worm-wheel C' to rotate the shaft 5 B', and thereby uncoil the chain E' and coil the chain D', and consequently turn the front axle to the right. In order to direct the engine to the left, the movement of the lever W will be reversed, so as to cause the wheel A' 10 to leave the wheel P and become engaged with the wheel R, thereby reversing the rotation of the shafts U and B', and consequently causing the latter to uncoil chain D' and tighten and coil the chain E', so as to turn the front 15 axle to the left. The engine is thus adapted to be controlled by the driver or engineer by simply moving the lever W.

Having thus described my invention, I claim—

20 The combination, in a traction-engine, of

the pivoted axle, the shaft or winch B', the chains coiled in opposite directions on the winch and attached to the pivoted axle, the shaft L, geared to the crank-shaft of the engine, the bearing M for said shaft having the 25 horizontal portion S, provided with the longitudinal slot T, the wheels P R, rigidly secured to the shaft L, the laterally-movable shaft U, geared to the winch, and having its upper end working in slot T and provided with the wheel 30 A', arranged between the wheels P R, the lever W, and the link Y, connecting the same to the shaft U, substantially as described.

In testimony that I claim the foregoing as my own I have hereto affixed my signature in 35 presence of two witnesses.

CHARLES AUGUSTUS COPELAND.
